UNITED STATES PATENT OFFICE.

JOSEPH D. NIEDERLITZ, OF ROCHESTER, NEW YORK.

PACK OF PLAYING CARDS.

Application filed August 23, 1928. Serial No. 301,551.

The present invention relates to a pack of playing cards and an object of the invention is to provide a pack of fifty-four cards having eight suits making it possible in auction bids, not only to be able to name a single suit as trump, but also to be able to bid on any two suits, viz, a first or leading trump single or double and any suit as a second, the first or major trump suit to carry honors. 5

10 Another object is to provide a pack of playing cards by which games heretofore requiring two separate packs may be played. Still another object is to provide a pack of cards which for certain games offers fifty- 15

two four suit cards; for other games fifty-four single and double cards and for still other games fifty-four eight suit cards. A further object is to provide a pack of playing cards having two and three distinct or separate 20

values for like characters or suit, according to games played, as for instance, in pinochle the indexed characters represent single and double values; in poker, a pair of jacks in the insert or frame represent the lowest 25

value, a pair of jacks in single indexed suit, second value and a pair of double jacks represent third or highest value; and in bridge, a bid on a single suit followed by a single 30

of another suit as second trump may prove of greater value than a bid on doubles. 35

To these and other ends, the invention consists of certain parts and combinations of parts, all of which will be hereinafter described: the novel features being pointed out in the appended claims. 40

In the drawings:

Fig. 1 is a face view of fragments of the fifty-four cards entering into the pack; and

Fig. 2 is a face view of one of the cards 45

complete.

In the illustrated embodiment of the invention, the pack comprises fifty-four cards 1. These cards are by characters 2 divided into eight groups. The group distinguishing characters are, in this instance, the usual four group distinguishing characters of an ordinary pack of cards such as diamonds, hearts, clubs and spades, colored as usual 50

red and black, together with four new group distinguishing characters, one consisting of 50 double spades with a star above, one of double hearts with a chess above and one of double diamonds, and one of double clubs. 55

The groups established by the group distinguishing characters 2 have their cards distinguished from each other by value distinguishing characters 3 which are the same in the eight groups and which are the same as those of the ordinary playing cards except that the numbers 2 to 7 inclusive are 60 eliminated. Each group has a value distinguishing character consisting of one of the value distinguishing characters 8 to 10 and J, Q, K and A. In other words, for certain games four single and four new double 65

suits are available and for other games eight suits are obtainable. This results in provision of a pack of fifty-four cards of eight different suits. 70

Means is also provided in the form of characters 4 for dividing the pack into four other different groups or suits, the characters indicated in the four groups being different from each other and consisting of the well-known characters diamond, club, heart and 75 spade colored as in the ordinary pack and arranged at the centers of the cards each preferably in a frame 5. The individual cards of the four groups or suits are distinguished by characters 6 which are the same in each of the four groups and are also the same as the distinguishing characters in an ordinary pack of cards namely 2 to 10 inclusive and J, K, Q and A. As these four groups only require fifty-two cards, two of the fifty- 80

four cards are provided with the word "Joker" as indicated at 7, thus making two 85 master cards in the pack.

To the end that the cards may be played like a game of dominoes, each card may 90 within the frame 5 be provided with numerals at opposite ends of the frame or on opposite sides of the center of the card, the numerals taking place of the different number of dots arranged at opposite ends of a 95 domino piece.

This pack of cards may be used in the same manner as the ordinary pack of playing cards. A new rule can be maintained by bidding on a first or leading trump and 5 making any suit the secondary trump.

Two to six players can score tricks or points as follows:

- 2 hands 27 tricks at 10—270 or 54 cards 5 each 270.
- 10 3 hands 18 tricks at 15—270 or 54 cards 5 each 270.
- 6 hands 9 tricks at 30—270 or 54 cards 5 each 270.
- 4 hands (discard 2) 13 tricks at 20—260 or 15 52 cards 5 each 260.
- 5 hands (discard 4) 10 tricks at 25—250 or 50 cards 5 each 250.

In bridge this will open up many new hands. By discarding the two double eights 20 there will remain six double and seven single trumps, the star and chess as a symbol or suit being ignored.

Pinochle or bezique players by discarding six eights and ignoring the star and chess 25 symbol will find additional melding features. Four single aces 100, four double aces 200, two single and two double (one of each suit) 100. A, 10, K, Q, J single trump 150, double trump 300 and so on through the chain of 30 melding or the custom of the players.

In poker, by tallying with the star and chess or double suit, five actual aces may be obtained or five of any kind down to eights, as well as double pairs double straights and 35 double flushes, ranking higher than single pairs, straights or flushes or still higher than those in the insert, if the three divisions are used at option or agreement by players.

Players of other intricate games, such as 40 skat, with its set of standard trumps, and the various solo games, where five players may take part and two always play against the bidder, will find this pack applicable to the various forms of strategy used in arriving 45 at their bids besides opening many new avenues of zeal.

For euchre, pedro or auction pitch, sixty-six etc. requiring a small number of cards, the insert suit can be used, likewise for 50 matching games, fan tan, solitaire, etc. including dominos from blank one to double nine.

What I claim as my invention and desire to secure by Letters Patent is:

1. A pack of playing cards comprising 55 fifty-four cards which have characters thereon dividing the cards into eight suits and also value characters on the different cards of each suit, the value characters of the different suits being the same type. 60

2. A pack of playing cards comprising fifty-four cards which have characters thereon dividing the cards into eight suits and also value characters on the different cards of each suit, the value characters of the different suits being the same, said cards also having other characters thereon dividing the cards into four suits of thirteen each, the remaining two cards being marked to form 65 master cards. 70

3. A pack of playing cards comprising fifty-four cards having two sets of suit characters, one dividing the pack into four suits and the other dividing the pack into eight 75 suits. 80

4. A pack of playing cards comprising fifty-four cards and having two sets of suit characters, one dividing the pack into four suits and the other dividing the pack into eight suits, those dividing the pack into 80 eight suits being double characters, each double character comprising two of one of the single suit forming characters. 90

5. A pack of playing cards comprising fifty-four cards and having two sets of suit 85 characters one dividing the pack into four suits and the other dividing the pack into eight suits, those dividing the pack into eight suits being double characters, each double character comprising two of one of the single suit forming characters, one of the double character suits being in black and having a star thereon, and the other of the double character suits being in red and having a chess symbol thereon. 95

6. A pack of playing cards comprising fifty-four cards having characters and values thereon divided in such a manner that they may be used as different decks, said cards also having characters thereon positioned at 100 opposite sides of the centers of the cards giving a domino value to each card.

JOSEPH D. NIEDERLITZ.
